Primary Examiner — Elizabeth J Oswecki(74) *Attorney, Agent, or Firm* — Kirk A. Buhler; Buhler & Associates Patenting(57) **CLAIM**

The ornamental design for a collapsible anti-theft box, as shown and described.

DESCRIPTION

FIG. 1 is a top plan view of a collapsible anti-theft box showing my new design;

FIG. 2 is a front elevation view of FIG. 1;

FIG. 3 is a bottom plan view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is another right-side elevation view of FIG. 1, with the top lid in a partially opened position;

FIG. 8 is a top, left perspective view of FIG. 1, with the lid in a partially opened position; and,

FIG. 9 is a top, left perspective view of FIG. 8, shown in a folded position.

The broken lines in FIGS. 1, 3, 5, 6, 7, 8 and 9 are for illustrative purposes only and form no part of the claimed design.

1 Claim, 5 Drawing Sheets(56)
